DISPENSING CABINET

Filed July 28, 1925

UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF MAINE.

DISPENSING CABINET.

Application filed July 23, 1925. Serial No. 46,578.

This invention has relation to towel dispensing cabinets, particularly those from which superposed interleaved sheets such as paper towels may be successively removed. 5 The paper towels in such cases are usually folded back and forth several times, the last fold of each towel overlapping and engaging the first fold of the next towel in the packet within the cabinet, so that when one towel is 10 withdrawn from the cabinet, the adjacent end of the next towel emerges so that it may be grasped. Heretofore such cabinets have found application in the wash rooms of large buildings and hotels, but have not been used 15 extensively for household or similar purposes.

The object of the present invention, generally stated, is to provide towel dispensing cabinet construction of a type which will be 20 simple in construction and which will render efficient service in operation.

One feature of the invention relates to a construction by which the sheets may be removed from the lower end of the cabinet, the 25 superposed sheets being guided to the emerging slot at the lower end of the cabinet by suitable guiding means provided within the cabinet. Other features of the invention relate to construction which permits the cabinet 30 to be opened for replenishing of the towel supply or for other purposes, and means tending to close the cabinet when it is open, so that the towels are not liable to accidental disengagement or permitted to fall out of 35 the cabinet. Further features and advantageous details and combination of parts will appear from a more complete description of an embodiment of the invention disclosed in the accompanying drawings, in which

40 Figure 1 is a perspective view of the cabinet fully opened.

Figure 2 is a longitudinal section along the lines 2—2 of Figure 1.

45 Figure 3 is an enlarged "life size" transverse section along the lines 3—3 of Figure 1.

Referring to the drawings, the cabinet as shown comprises a receptacle for housing a supply of interleaved sheets, indicated as a whole at A, hingedly secured to a back or 50 cover B. The cabinet is preferably constructed of sheet metal stampings, and the receptacle A may consist of several pieces which have been suitably fastened together, as by welding, or it may consist of an inte-

gral piece properly cut and bent to form, with certain of its edge portions suitably 55 fastened together, but is preferably formed by drawing or pressing a properly cut blank by suitable press-dies. The receptacle A as shown is of substantially rectangular or box form, and has an open back through which 60 towels may be inserted in the receptacle. The sides of the receptacle may have stamped raised portions D in the form of rectangular panels, or any other design, for the purpose 65 of ornamentation, as well as to make the cabinet strong and stiff.

To allow removal of the towels from the cabinet, the bottom of the receptacle is provided with a central elongated opening or slot 1 through which the towels may be successively withdrawn. The edges of the bottom defining the slot are rolled in the form of beads 2, to present a smooth finished surface and to offer little resistance to the towels as 70 they emerge from the receptacle. In order to 75 present the towels in proper position before emergence from the exit slot of the cabinet, within the receptacle A and welded or otherwise suitably secured to the ends 4 and 5, respectively, are the inclined leaves 6 and 7, 80 converging toward the ends of the exit slot 1. With such construction, a packet of towels 85 may be placed in the cabinet without paying particular attention to the proper arrangement of the sheets. The guides also act to 90 partially support the towels and to impose a slight frictional resistance to their passage toward the exit opening, to hold back the superposed sheets sufficiently to permit ready 95 withdrawal of the lowest sheet without, however, interfering with their normal downward progress toward the exit opening.

The receptacle A is supported in a manner to permit the cabinet to be opened at will 100 for replenishment of the towel supply, and is then automatically closed. For this purpose, the receptacle is provided at one of its ends 5 with rolled spaced elements or beads 8 and 9, serving as hinge members. These members are rotatably mounted on a pintle 105 10, secured to a pair of spaced beads or supporting members 12 and 13, at one end of the back or cover B, and between these members is a coil spring 15, one end 18 of which extends in the rear of the back B. The other 110 end 16 of the spring engages the outer face of the end 5 of the receptacle, so that upon

opening the cabinet the spring 15 is tensioned so as to force the receptacle back to its original position when it is left freely open.

- For the purpose of locking the case to the back, the other end of the back B is provided with a locking member 20 consisting of a flexible or springy metal strip, having a protuberance or catch 22, constructed to engage in a mating slot or hole 17 in the end 4 of the receptacle A and maintain the receptacle locked to the back. The outer end of the locking member 20 has a thumb element 19 by which the catch 22 may be disengaged from the slot and the receptacle A swung open. The back 15 is also provided with a plurality of openings or holes 21 therethrough, so that the receptacle may be conveniently secured to a wall, door, or other suitable supporting structure 30.
- 20 As shown in Figure 3, the towels are placed within the receptacle, the guides 6 and 7 directing them toward the opening in proper position, so that the end of the lowermost towel 25 protrudes through the opening and 25 may be grasped. In removing one towel, the adjacent end of the succeeding towel is presented through the opening, so that successive removal of the superposed towels within the receptacle may be accomplished.
- 30 It is to be noted that the construction described is simple and provides for the opening and automatic closing of the cabinet by simple means conveniently located and easily operated. Moreover, the towels may be inserted in the cabinet without particular attention to their position and proper removal thereof may be had. Because of the distinctive construction of the cabinet of the present invention, it is especially adapted for manufacture in small units, each to contain about 100 towels, and is particularly suitable for household or similar use. It may be produced inexpensively and sold cheaply as compared with towel cabinets now on the market, and is 45 thus suitable to more extensive use.

Having thus described an embodiment of this invention, it should be evident that it is susceptible of various changes and modifications without departing from its spirit or 50 scope as defined by the appended claims.

What I claim is:

1. A dispensing cabinet comprising a back for securement to a support, an open-back receptacle for housing a supply of interleaved

sheets hingedly secured thereto at one end 55 and having a slot at the bottom, through which said sheets may be successively withdrawn, and a pair of inclined leaves within and adjacent to the ends of said slot 60 and converging toward the ends of said slot for guiding said sheets in proper position toward said slot, said receptacle being swingably open from said back horizontally, so that sheets may be introduced into said receptacle through its open back. 65

2. A dispensing cabinet comprising a back for securement to a support, an open-back receptacle for housing a supply of interleaved sheets hingedly secured thereto at one end 70 and having a slot at the bottom through which said sheets may be successively withdrawn, means for locking said receptacle to said back, means tending to close and lock said receptacle to said back when the cabinet is open, and a pair of inclined leaves within and adjacent to the ends of said receptacle and converging toward the ends of said slot for guiding the sheets in proper position thereto. 75

3. A dispensing cabinet constructed of 80 sheet material comprising a back for securement to a support and having a pair of spaced rolled hinge elements at one end, an open back receptacle for housing a stack of interleaved sheets and having at one end a pair of spaced 85 rolled portions forming hinge elements, said receptacle having a slot at the bottom through which said sheets may be successively withdrawn, a pair of inclined leaves within and adjacent to the ends of said receptacle and converging toward the ends of said slot for guiding the sheets in proper position thereto, a pintle passing through said several hinge elements, a spring coiled about said pintle between said back elements and having one end 90 engaging the back and the other end engaging the end of said receptacle, thereby tending to force said receptacle against said back, and a springy metal strip on said back having a protuberance constructed to engage in a mating hole in said receptacle to maintain said receptacle locked to said back, said strip having a thumb element by means of which said protuberance may be disengaged from said hole. 95

In testimony whereof I have affixed my signature.

HOWARD PARKER.
